UNITED STATES PATENT OFFICE

AUSTIN L. STOWELL, OF NEW BRITAIN, CONNECTICUT, ASSIGNOR TO THE STANLEY WORKS, OF NEW BRITAIN, CONNECTICUT, A CORPORATION OF CONNECTICUT

BIT OR DRILL HOLDER

Application filed September 13, 1929. Serial No. 392,344.

This invention relates to holders or chucks particularly adapted for use on braces or bit stocks. Certain features of the present invention relate to a chuck of the type having a pair of jaws adapted to be cammed towards each other by a surrounding nose or cone, the jaws being normally urged apart by means comprising a pair of spring arms which are connected together externally of the chuck body, a chuck of this general type being disclosed in the patent to H. E. Parker No. 1,270,754, dated June 25th, 1918. Chucks of this general type have met with approval and are particularly advantageous in that the spring means for opening the jaws cannot be injured by the shank of the bit when the shank is inserted into the chuck. The chief disadvantage of a chuck of this type resides in the spring construction as heretofore made, that construction, as shown in said Parker patent, including a collar of substantial size and to which the spring arms are connected. The collar, which has been a closed ring, must fit reasonably close to the stem or turned-down portion of the chuck body leaving but a very narrow space therebetween in which dirt and rust are not only likely but very liable to gather so that the collar will not readily slide on the stem with that degree of freedom which is necessary to a properly operating chuck. Also, the spring means shown in said Parker patent is somewhat expensive to make, the springs are liable to become loose, and the spring means cannot be replaced without taking the chuck apart.

An aim of the present invention is to provide, in a chuck of this sort, improved spring means for normally urging the jaws apart which is not open to the above and other objections incident to the arrangement shown in said Parker patent.

More particularly, aims of the invention are to provide, in a chuck of this character, an improved spring which is not likely or liable to stick due to the collection of dirt or rust between the connecting portion of the spring and the stem on which it slides so that the spring means will always operate freely even after the chuck has been

in use for a considerable length of time; to provide an improved arrangement which will permit of ready replacement of the spring means without taking the chuck apart from the rest of the mechanism; to provide improved spring means which is extremely simple in construction and which can be made very inexpensively; to provide improved spring means in which any likelihood of the spring arms becoming loose or displaced relative to one another or to the connecting portion is entirely eliminated; and to provide an improved arrangement which will permit of shortening of the lengths of the steel parts of the chuck, except the jaws, so that a more compact and lighter construction is obtained, together with a saving in material and labor in manufacture.

The invention further relates to an improved ball bearing arrangement which may be used, for instance, for preventing relative axial movement between the sleeve and the nose piece but which will permit the sleeve to be more easily rotated so that the jaws may be more tightly clamped against the tool with less effort. Heretofore, it has been the practice to provide a separate nose ring secured to the sleeve proper by means of a screw and to interpose the anti-friction balls between the nose ring and the nose piece, or to provide a one-piece sleeve with an internal groove to which leads an opening through which the balls are inserted into the raceways, the opening being closed by means of a small screw. In either event, these constructions are open to certain objections and, particularly, the small screws introduce difficulties and expense in manufacture and assembly, and the screws not infrequently become loosened and displaced. In accordance with the present invention, improved means of a simplified and economic nature are provided for readily and effectively closing the opening leading to the ball raceways. My improved means may be very readily assembled and disassembled, while there is no likelihood of the same becoming accidentally displaced.

Other objects will be in part obvious and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the accompanying drawing, wherein I have shown, for illustrative purposes, one embodiment which the present invention may take:

Figure 1 is a side elevational view of the chuck;

Fig. 2 is a central longitudinal section therethrough;

Fig. 3 is a view showing, in elevation, the jaws and the spring means for urging the jaws apart;

Fig. 4 is an elevational view of the sleeve;

Fig. 5 is an elevational view of the chuck body, one of the jaws and the spring means;

Fig. 6 is a view looking at the forward end of the chuck body, the spring means being shown in dotted lines;

Fig. 7 is a perspective view of a ring for holding in place the plug for the loading hole;

Figs. 8 and 9 are face and edge views, respectively, of the plug member; and

Fig. 10 is an enlarged detail view showing, in section, the manner in which the loading hole is plugged and the manner in which the plug is held in place.

In the accompanying drawing, I have shown my improvements incorporated in a chuck having a chuck body and jaws of an old and well-known construction, but it is to be understood that this disclosure is by way of illustration only, it being obvious that my improvements may be incorporated in chucks constructed other than that herein disclosed. The letter A denotes a chuck body provided with an external thread 10 and a reduced or turned-down stem 11. The outer end of the body is hollowed out and is provided at each side with a notch 12 so as to accommodate the rear ends of the jaws. Also, at each side of the chuck body and leading from the bases of the notches 12 to the stem 11, is a longitudinally extending groove 13 for accommodating the arms of the spring. B, B denote the jaws which, as stated, may be of any suitable construction. The nose piece is indicated by the letter C, and the sleeve by the letter D, the latter having an internal thread 14 adapted to receive the thread 10 so that, when the sleeve is rotated, it, together with the nose piece C, is advanced or withdrawn longitudinally depending on the direction of rotation of the sleeve.

In accordance with the present invention, the means for urging the jaws apart consists of a member having a pair of spring arms 25, 25 and a connecting portion 26, the connecting portion extending but partially

around the stem 11, in the present instance this connecting portion being semi-circular. By preference, this spring member consists of an integral length of wire round in cross section. The free ends of the arms 25 are turned outwardly, as at 27, so that they may be removably engaged with the jaw members in the usual and well-known manner shown in Figs. 2 and 3. It will be observed that the semi-circular connecting portion 26 of the spring wire fits against and is adapted to freely slide along the stem 11, and the arms 25 are free to slide in the grooves 13 when the jaws are moved with respect to the chuck body. Since the connecting portion 26 between the arms is (as compared to the ring or collar to which the spring arms have heretofore been connected) relatively small in cross section and has not a rigid relation with respect to the stem 11, there is no likelihood or possibility of the connecting portion sticking or becoming wedged or clogged due to the collection of dirt, rust or other foreign matter between the connecting portion and the stem. The spring may be readily assembled onto the body portion, all that is necessary being to bring the connecting portion against the stem and spring the arms into the grooves 13 before the sleeve is screwed onto the body portion. The spring can be just as easily removed. It is important to note that the spring may be very easily and quickly replaced in the event that it has become broken without removing the chuck body from the member which carries the same. It is only necessary to unscrew the sleeve D from the chuck body A. Heretofore, where a ring has been employed to which the spring arms are connected, it has been necessary to make the stem 11 of the chuck body of such length as to allow for the width or length of the collar and also for sliding movement thereof. In the present instance, since the connecting portion is of relatively small cross section in the direction of the length of the stem, the stem may be considerably shortened, and also, the sleeve D may be shortened, features of importance as they permit of a lightening of the chuck, the production of a more compact arrangement which will make it possible to get in to closer quarters, and which will result in a saving in manufacture. The spring means, being formed of one integral piece of wire, may be manufactured at a very low cost. Since the spring means are of one integral piece, there is no possibility of the spring arms working loose from the connecting member as was the case where these arms were fastened into a collar.

My improved means for preventing the roller balls from coming out of the loading hole and being lost will now be described. The sleeve has an internal raceway or groove 30, and the nose piece C has a corresponding raceway 31 registering therewith, and in these

- raceways the ball bearings 32 work. About the sleeve D is a shallow groove 33 which is preferably square in cross section, and leading from the bottom of this groove to the 5 raceway 30 is a loading opening 34 which is adapted to be closed after the balls are inserted into the raceways by a plug member which is shown most clearly in Figs. 8 and 9. This plug member, which is preferably 10 formed of a small thin strip of sheet metal, has, at its central portion, a pressed out or drawn up boss 35 to either side of which is a wing 36. The plug is preferably formed of resilient metal and is of such diameter that 15 it may be wedged into the loading hole. The stud portion is of such height as to just clear the balls as they pass around the raceways. A split ring 40 is adapted to fit in the groove 33 for the purpose of holding the plug member 20 in place. The ring is preferably made out of square or rectangular steel stock, a suitable length of stock being cut off and then bent into circular form. The split steel ring 25 40 is preferably no thicker than the depth of the groove 33 so that, when the ring is in place, it will not project beyond the periphery of the sleeve, and thus the sleeve and ring 30 will present an unbroken surface.
- The manner in which the balls are held in place will be readily understood. After the balls are inserted in the raceways, the plug piece is brought into the groove, and the boss 35 is forced into the loading opening. Then the split ring is slipped over the sleeve and brought into registry with the groove 33, whereupon the spring will contract snugly 35 into this groove. The ring will securely hold the plug in place. Thus, there is provided safe and reliable means for simply and effectively closing the loading hole. This arrangement results in a more simple and better chuck at a lower cost. If desired, the external periphery of the ring 40 may be colored to contrast with the color of the sleeve in 40 order to add a pleasing decoration to the chuck sleeve.
- As many changes could be made in the above construction and many apparently 45 widely different embodiments of this invention could be made without departing from the scope thereof, it is intended that all matter contained in the above description or shown in the accompanying drawing shall be interpreted as illustrative and not in a limiting sense.
- It is also to be understood that the language used in the following claims is intended to cover all of the generic and specific features of the invention herein described and all 50 statements of the scope of the invention which, as a matter of language, might be said to fall therebetween.
- I claim as my invention:
1. In a chuck of the character described, 55 means for urging the jaws apart comprising
  2. In a chuck of the character described, 60 means for urging the jaws apart comprising a pair of resilient arms and a parti-circular portion connecting the ends of said arms, said arms being substantially normal to the plane of said parti-circular portion and said connecting portion being adapted to receive and slide on a chuck body extending longitudinally between the arms. 65
  3. In a chuck of the character described, 70 means for urging the jaws apart comprising a pair of resilient arms provided at their free ends with means for connecting the same to the jaws and a semi-circular connecting portion between the other ends of said arms, said arms being substantially normal to the plane of said connecting portion and said connecting portion being adapted to receive and slide on a chuck body extending longitudinally between the arms. 75
  4. In a chuck of the character described, 80 means for urging the jaws apart comprising a single integral length of resilient wire having a semi-circular connecting portion and an arm extending from each end of said connecting portion, said arms being substantially normal to said connecting portions and said connecting portion being adapted to receive and slide on a chuck body extending longitudinally between the arms. 85
  5. In a chuck of the character described, 90 a body portion provided with recesses at its forward end for accommodating the chuck jaws, a reduced portion at its rear end, and grooves leading from the reduced portion to said recesses; and means for urging the jaws apart comprising a semi-circular connecting portion engaging the external periphery of said reduced portion and arms extending therefrom and engaging in said grooves, said semi-circular connecting portion extending partially around said reduced portion and being slidably longitudinally thereof. 95
  6. In a chuck of the character described, 100 a chuck body provided with recesses at its forward end, a reduced portion at its rear end, and grooves leading from the reduced portion to said recesses; jaws in the forward end of said body, a shell threaded on said body and having a nose piece cooperating with said jaws, and means for urging said jaws apart comprising a single length of resilient wire and having a semi-circular connecting portion slidably engaging said reduced portion and arms projecting from the ends of said connecting portion and extending through said grooves and connected to said jaws, said arms being substantially 105
  7. In a chuck of the character described, 110 means for urging the jaws apart comprising a single length of resilient wire having a semi-circular connecting portion and an arm extending from each end of said connecting portion, said arms being substantially normal to said connecting portions and said connecting portion being adapted to receive and slide on a chuck body extending longitudinally between the arms. 115
  8. In a chuck of the character described, 120 means for urging the jaws apart comprising a single length of resilient wire having a semi-circular connecting portion and an arm extending from each end of said connecting portion, said arms being substantially normal to said connecting portions and said connecting portion being adapted to receive and slide on a chuck body extending longitudinally between the arms. 125
  9. In a chuck of the character described, 130 means for urging the jaws apart comprising a single length of resilient wire having a semi-circular connecting portion and an arm extending from each end of said connecting portion, said arms being substantially normal to said connecting portions and said connecting portion being adapted to receive and slide on a chuck body extending longitudinally between the arms. 135

normal to said semi-circular connecting portion.

7. In combination, a sleeve provided with an internal raceway, an external groove, and a loading opening leading from the groove to the raceway; a plug member having a boss portion fitting in said opening and wings engaging in said groove, and a contractile ring in said groove for holding said plug in place.

10 8. In combination, a sleeve provided with an internal raceway, an external groove, and a loading opening leading from the groove to the raceway; a plug member having a resilient boss portion wedgedly fitting in said opening and wings fitting in said groove, and a split resilient ring fitting in said groove and over said plug member.
